CLAIM

The ornamental design for a display screen with graphical user interface or portion thereof, as shown and described.

DESCRIPTION

The present application is related to U.S. Design patent application Ser. No. 29/488,692, and to U.S. Design patent application Ser. No. 29/488,695, the entire disclosures of which are incorporated herein by reference.

FIG. 1 is a front view of a display screen with graphical user interface or a portion thereof, according to a first image of a first embodiment;

FIG. 2 is a front view of a display screen with graphical user interface or a portion thereof, according to a second image of the first embodiment;

FIG. 3 is a front view of a display screen with graphical user interface or a portion thereof, according to a first image of a second embodiment; and,

FIG. 4 is a front view of a display screen with graphical user interface or a portion thereof, according to a second image of the second embodiment.

The broken lines showing portions of the graphical user interface and display screen are included for the purpose of illustrating portions of the article and form no part of the claimed design. In the figures, the perimeters of the portion of the underlying display screen and the graphical user interface are understood to be flush.

The image in the first embodiment transitions sequentially between the images shown in FIGS. 1-2. The image in the second embodiment transitions sequentially between the images shown in FIGS. 3-4. The process or period in which an image transitions to another forms no part of the claimed design.
